UNITED STATES PATENT OFFICE.

MYHALZ H. D. PRIDDY, OF RICHMOND, CALIFORNIA.

DAIRY-CAN.

1,237,093.

Specification of Letters Patent. Patented Aug. 14, 1917.

Application filed June 20, 1916. Serial No. 104,744.

To all whom it may concern:

Be it known that I, MYHALZ H. D. PRIDDY, a citizen of the United States, residing at Richmond, in the county of Contra Costa and State of California, have invented new and useful Improvements in Dairy-Cans, of which the following is a specification.

This invention relates to improvements in cans and other like vessels, especially dairy cans such as are used in the transportation of milk and other dairy products, the object of the invention being to provide an improved can of this type which is extremely light, is very strong and durable, is non-corrodible, and is adapted to be easily handled and is destitute of seams or rivets in the sides, shoulder, or neck.

The invention consists in the features of construction, combination, and arrangement 20 of devices, hereinafter fully described and claimed.

In the accompanying drawings:

Figure 1 is a side elevation of a dairy can constructed and arranged in accordance with 25 my invention.

Fig. 2 is a detail sectional view on a larger scale, of the upper portion of the can.

Fig. 3 is a similar view of the lower portion of the can.

30 Figs. 4, 5, and 6, are detail views.

Fig. 7 is a detailed plan of the collar or neck ring.

Fig. 8 is a detailed sectional view showing 35 one of the catches engaging the flange of the collar.

The body 1 of my improved can is made of aluminum and is formed with an upwardly contracted shoulder 2, and a cylindrical neck 3. In the manufacture of the 40 can, the body with the shoulder and neck are made all in one piece by first running the same from molten metal into a mold of the required shape of the can. The mold or shape is however less in size but thicker than 45 the can when finished. As soon as the "can form" can be removed from the mold, the same is placed between two rollers which roll the metal while still hot and the rolling is continued until a wall of the required 50 thickness is obtained. Hence the can body is integral and is entirely without a seam or rivet.

The bottom 4 is also made of aluminum and is pressed from the metal in hot sheet 55 form, immediately after the metal has been cooled from the molten state to a hardened

state. The bottom is concaved as shown and is formed with a surrounding downwardly extending flange 5, which is riveted snugly in the lower end of the body 1 and is riveted thereto as at 6.

The cover 7 is also made of aluminum and is pressed in the same manner as the bottom and is adapted to fit snugly around the neck of the can.

At the base of the can is a ring 8 which is preferably made of malleable iron but which may be made of any suitable material. The base ring is formed at its inner side with a channel 9 to receive the lower edges of the 70 can body or wall and the flange 5 of the bottom and the outer wall 10 formed by the channel is higher than the inner wall 11 and extends around the base of the body. The base ring is of greater diameter than, and 75 extends outwardly from the body, as at 12, and is formed with an outer depending bearing flange 13 which bears on the floor and supports the can.

To further protect the bottom of the can, I 80 provide a sheet metal disk 14 which is fitted under the portion 12 of the base ring and extends across the same.

A collar 15, which is right angular in cross section, is fitted around the base of the 85 neck, so that its annular flange 16 projects outwardly from the neck. This collar is also preferably made of malleable iron or may be made of any suitable material and is provided with notches 10^a.

A truss ring 17 is fitted around the larger lower portion of the shoulder 2 of the can, the wall of said truss ring having a cylindrical portion 18 which extends around the larger cylindrical portion of the can body 95 and also having a frusto-conical portion 19, which fits around the shoulder. The truss ring also has an outwardly extending annular flange 20 which is provided with notches 21 at suitable distances apart to receive truss rods 22. The lower ends of the truss rods pass through openings in the flange 12 of the base ring and also through the disk 14 and are provided with nuts or other suitable securing devices 23, the upper 100 ends of the truss rods being provided with hooks 24, the bills of which are vertical and extend downwardly through openings in the flange 16 of the neck ring 15.

The can body being made of aluminum, 110 is extremely light, but is also comparatively soft, the base ring, truss ring, neck ring and

truss rods serving to protect the can and prevent it from being dented and deformed and at the same time greatly facilitating the handling of the can. To enable the can to be readily lifted, the truss ring is provided at opposite sides with inverted U-shaped lifts or handles 25 as shown.

Secured across the top of the cover 7 is a flat steel spring 26, having down turned 10 ends or arms 27, which are provided with catches 28, for engaging in the notches 10^a of the flange 16 of the collar, and thereby securely and yet detachably fasten the cover, and also prevent the cover from slipping 15 when the can is tilted and rolled.

The cover is also provided with a handle ring 29, the diameter of which exceeds that of the cover. Said handle ring is connected to and secured above the cover by means of 20 a suitable number of braces 30. These braces project a slight distance below the lower edge of the cover, bear against the upper side of the collar 15 and hence prevent any weight which may be placed on the can 25 from being imposed upon the neck of the can.

When the cans are arranged, one above the other, the metal disk 14 of one of the cans bears on the handle ring 29 of the next can 30 below and hence the top and bottom of each can are protected.

By grasping the handle ring and inclining the can so that one side of its base ring bears on the floor, the can may be readily 35 rolled in any desired direction as will be understood.

Having described the invention, what is claimed is:

1. A can of the class described having protecting means including a neck ring having 40 an outstanding flange provided with notches, and a cover for the can having spring catches to engage the notches and under the flange of the neck ring and detachably securing the cover in place. 45

2. A can of the class described having a neck ring and also having a cover, a handle ring above the cover and braces connecting the handle ring to the cover and projecting slightly below the cover and bearing on the 50 neck ring.

3. In combination with a can having an upwardly contracted shoulder and a cylindrical neck of less diameter than the body of the can, a neck ring on the neck of the 55 can, a truss ring around said shoulder, a base ring under the bottom of the can, truss rods connecting the base and neck rings and having inwardly turned upper portions and bearing against the truss ring, said truss 60 rods having their upper ends detachably engaged with the neck ring and having their lower ends arranged in openings in the base ring, a disk fitted under the base ring and spaced from and protecting the can bottom, 65 said rods extending also through openings in said disk and nuts on the lower ends of the rods and bearing against the under side of said disk.

In testimony whereof I affix my signature. 70

MYHALZ H. D. PRIDDY.
